CIGARETTE SNUFFER

Glenn Gary Davis and Robert Walton Dahlin, Palm Springs, Calif., assignors of fifty percent to Morris Lavine

Filed Feb. 24, 1967, Ser. No. 618,504
U.S. Cl. 131—256 1 Claim
Int. Cl. A24f 13/18, 19/14, 15/18

ABSTRACT OF THE DISCLOSURE

A tubular cigarette snuffer having an annular groove to snap into place in an ash tray adapter or the like.

Background of the invention

This invention relates to devices for extinguishing cigarettes or the like, and more particularly to a snuffer.

Although the invention has been found useful when employed in an ash tray of an automobile, it is, of course, not limited to this particular type of application.

In the past, it has been the practice to provide a projection in an ash tray of an automobile to remove the ash tray from a cigarette to extinguish it. However, these devices frequently do not perform their intended function.

Summary of the invention

In accordance with the device of the present invention, the above described and other disadvantages of the prior art are overcome by providing a snuffer for a cigarette or the like which may be used with an adapter to fit it into an automobile ash tray.

Unexpectedly, a snuffer which closely fits a cigarette puts out the cigarette rapidly even when the ash is not squashed and the cigarette is extinguished, ash down.

The above-described and other advantages of the present invention will be better understood from the following description when considered in connection with the accompanying drawings.

Brief description of the drawings

FIG. 1 is a top plan view of the cigarette snuffer of the present invention;

FIG. 2 is a sectional view of the apparatus taken on the line 2—2 shown in FIG. 1;

FIG. 3 is a side elevational view thereof;

FIG. 4 is a side elevational view of an adaptor employed with the present invention;

FIG. 5 is a top plan view of the adaptor; and

FIG. 6 is a perspective view illustrating an alternate use of the invention.

2

Description of the preferred embodiments

In FIG. 1, a cigarette snuffer is indicated at 10 pressed through an adaptor 11. As shown in FIG. 2, snuffer 10 has a flange 12 which fits on the top surface of the adaptor 11. Snuffer 10 has a groove 13 immediately below flange 12. Adaptor 11 has a hole 14 therethrough. Snuffer 10 is pushed through hole 14 and is snap fit in adaptor 11. Adaptor 11 has a projection 15 which is adapted to fit in a hole 16 of an ash tray plate 17.

As shown in FIG. 4, projection 15 has prongs 18 and 19 which spring together to allow projection 15 to snap fit into hole 16. Projection 15 has a rib 20 therearound to retain it in plate 17.

An alternate position for snuffer 10 is shown in FIG. 6 in the top of a flip top type of cigarette package.

We claim:

1. In combination, a cigarette package having a closed bottom and an open top and a relatively hard paper top having a horizontal member swingable from open to closed positions relative to said top, said paper top including an opening therethrough; and a hollow cylindrical receptacle having a closed lower end and an open end, said open end including an enlarged horizontal flange and a circumferentially extending groove on the outer cylindrical surface thereof immediately adjacent and below the flange, such that when the receptacle is fully received within the opening of the paper top, the portions thereof defining the opening are anchored within said groove.
